UNITED STATES PATENT OFFICE.

AXEL S. VOGT, OF ALTOONA, PENNSYLVANIA.

PISTON-ROD.

1,112,737.

Specification of Letters Patent. Patented Oct. 6, 1914.

Application filed February 24, 1914. Serial No. 820,728.

To all whom it may concern:

Be it known that I, AXEL S. VOGT, a subject of the King of Sweden, residing at Altoona, in the county of Blair and State of Pennsylvania, have invented certain new and useful Improvements in Piston-Rods, of which the following is a specification.

This invention relates to a novel piston rod construction used chiefly in connection with modern high speed locomotives.

In the design and construction of modern railway locomotives lightness and strength of parts are two important features sought to be combined to secure a maximum efficiency, the former because the reduction of weight decreases the weight of the reciprocating mass, also the amount of counterbalance added to the driving wheels, and the latter because it is a characteristic necessary to this important power transmitting element of the locomotive.

Various expedients have been used to reduce the weight of locomotive pistons and piston rods with more or less ultimate success, and it is to this end that this present invention is directed; that is to say, the invention has in view a reduction of weight of the reciprocating parts by lessening the weight of the piston rod which is one of the reciprocating parts, and to this end contemplates a novel and improved hollow piston rod which possesses ample strength and durability without great weight.

Though the principal object of the invention is as stated above, it is believed that other objects of the same will be more readily apparent as the nature of the invention is better understood and its various features and advantages brought out in the following specification and claims.

In the drawings Figure 1 is a sectional view of a steam engine cylinder and steam chest showing the application of the invention. Fig. 2 is a view of the metal tube at the end of the third step of forming the piston rod, the central bore being indicated by dotted lines, and the enlarged portion clearly shown. Fig. 3 is a view of the piston rod as it appears at the end of the swaging operation, and after certain portions thereof have been provided with threads. Fig. 4 is an end view of the construction shown in Fig. 3. Fig. 5 is a detail-top plan view of the crosshead end of the piston rod. Fig. 6 is a sectional view on the line 6—6 of Fig. 5.

Similar reference characters designate corresponding parts throughout the several figures of the drawings.

Referring to the device as shown in the accompanying drawings, it will be observed that the construction and arrangement of the same renders it especially useful as a piston rod for locomotive cylinders, but at the same time it will be understood that the application is not limited to the use of the rod in an engine of this character.

In Fig. 1 the hollow piston rod is shown in connection with the parts of a steam engine to which it particularly relates, namely, a portion of the valve gear A, crosshead B and cylinder C.

In carrying out the present invention I take a steel shaft 1 of sufficient length and rough diameter to form the finished piston rod. This steel shaft I first rough turn, leaving the crosshead end 3, the piston fit portion 4 and the piston rod extension shoe fit end 5 of larger diameter than the remaining portion *a* and *b* of the rod. After the rough turning is accomplished I proceed to drill a uniform diameter of hole 2 lengthwise through the rod, using the lathe center as a drill center. After the central hole 2 has been drilled I proceed to heat the enlarged portions of the rod for the purpose of swaging or squeezing together under a steam hammer, together with proper shaped dies, to properly force the periphery of the rod toward the center. This action has the effect of reducing the diameter of the hole 2 at the crosshead end 3 of the rod, the piston fit portion 4 and the piston rod guide shoe end 5, as well as to increase the density of the steel at these portions. After this operation has been completed, the rod is then heat treated and finished ready to be assembled with the locomotive.

In finishing the crosshead portion 3 of the rod 1 the same is tapered toward the end of the rod as at 6 and formed with a keeper, or crosshead key, slot 7. The taper 6 of the end of the rod not only permits the same to firmly seat in the socket 8 in the portion 9 of the crosshead B so that it may be readily secured thereto, but at the same time facilitates the assembling of the parts.

The central or piston head portion 4 is provided during the finishing step with an abutment flange 10 and a tapered head seat 11 which tapers away from the said flange and terminates in a portion 12 which is

subsequently threaded. Thus it will be apparent that this construction provides for carrying the piston head 13 so that it may perform its usual function in the cylinders 5 C and at the same time be secured firmly in place by means of the clamping nut 14, adjustable on the threaded portion 12, so that it may clamp the said head 13 between itself and the flange 10.

10 With reference to the shoe guide end 5 of the rod it will be noticed that the same is reduced to cylindrical portions of different diameters, the largest portion 15 being designed to receive the wear shoe 16 that 15 slides in the guideway G, while the smaller portion 17 is threaded to receive a nut 18 to lock the shoe to the end of the rod.

A distinctive feature of the present invention resides in forming the rod 1 with 20 densified portions to strengthen the same where it is to be connected with other engine parts, and at the same time leaving the rod with suitable bearing portions 19 and 20 between said densified portions which still 25 have their original diameter and bore. The said bearing portions 19 and 20 are adapted to slide through the ends of the cylinder C in the usual manner, but by reason of their construction considerable strength is pro- 30 vided while at the same time having the additional feature of being much lighter than the ordinary solid piston rod.

From the foregoing description it is be-

lieved that it will be obvious that the hollow piston rod contemplated by the present invention, is a thoroughly practical and useful construction, especially designed and adapted to reduce the weight incident to solid constructions in devices of a similar character. It is believed that other advantages of the invention will be apparent without further description.

I claim:

1. A hollow piston rod for engines having densified end portions, an intermediate 45 densified piston-head portion, and bearing portions between said intermediate piston head portion and said end portions.

2. A hollow piston rod for engines having densified end portions, an intermediate 50 densified piston head portion including an annular flange and a clamping nut, and bearing portions between said intermediate piston head portions and said end portions.

3. A hollow piston rod for engines having 55 a slotted cross-head portion, an intermediate piston head portion, and a reduced cylindrical guide shoe portion including a clamping nut.

In testimony whereof I affix my signature 60 in presence of two witnesses.

AXEL S. VOGT.
